UNITED STATES PATENT OFFICE

MOLLIE L. GROSSMAN AND JOSEPH N. LOWE, OF NEW YORK, N. Y.

HAT BAG

Application filed August 19, 1922. Serial No. 563,035.

The invention relates to a hand bag intended primarily to receive a lady's hat and also to hold such additional light weight articles as a woman might desire to carry with her on an automobile trip or the like. The bag is designed to hold a hat without in any manner crushing it, and it is provided with a handle by which the bag may be suspended from the hand or hung about the wrist or supported from a hook or the like in an automobile or in a railway car. The bag is also of such character that its appearance is in no manner objectionable whether being carried by hand or suspended in a limousine. The exterior fabric of the bag will preferably be a fine grade of black oil-cloth or waterproof fabric and the interior of the bag will preferably be lined with a colored or figured woven fabric of attractive character. The bag is in the general form of a shallow drum, comprising a peripheral band of suitable width and disks secured at their edges to the edges of said band. At the upper side of the drum-like bag, the peripheral band thereof, throughout nearly one half its length, is of special construction and composed of two overlapping segmental members adapted to be fastened together by snap fasteners or the like, for securing the bag in closed condition, or turned outwardly one from the other, for opening the bag to permit the withdrawal of a hat or other article.

Since the bags are of flexible material and frequently placed flatwise one upon another on a store counter or the like for display purposes, we preferably insert within the bags a strip or strips of pasteboard or fibreboard extending around the inner side of the peripheral band and conforming in outline thereto, as means for stiffening the peripheral portions of the bags and preventing the collapse of the bags when on display or held in stock. We may insert the stiffening or reinforcing strips between the outer fabric and the lining of the peripheral band of the bag or insert the same within the bag to lie against said lining, having used both methods of reinforcement with success, and in accordance with either method the reinforce-

ing or stiffening strips may be removed when it is desired to have a light, soft, flexible bag for use.

The invention will be fully understood from the detailed description hereinafter presented, reference being had to the accompanying drawings, in which:

Fig. 1 is a perspective view of the bag of our invention shown in partly open condition;

Fig. 2 is a like view of the same shown in closed condition;

Fig. 3 is a central vertical longitudinal section through the same taken on the dotted line 3—3 of Fig. 4.

Fig. 4 is a vertical transverse section through the same taken on the dotted line 4—4 of Fig. 3;

Fig. 5 is a horizontal section, on a larger scale, through a portion of the bag taken on the dotted line 5—5 of Fig. 4, and

Fig. 6 is a vertical section of a portion of the bag corresponding with the section at the right hand side of Fig. 3 but shown enlarged for the sake of clearness of illustration.

In the drawings 10 designates the peripheral or band portion of the bag as a whole, and 11, 12 indicate the two opposite sides of the bag which are in the form of disks and lined with a suitable fabric 13, also in the form of disks. The body portion of the band 10 has a suitable fabric lining 14.

The band 10 comprises a main body portion 15 and a top or cover-section 16, the portion 15 being of suitable width and defining a circle, and the section 16 defining substantially a semicircle and normally lying upon and covering substantially the upper half of the body portion 15. The cover section 16 is formed of the same character of material as the body portion 15 and has a fabric lining 17.

At its lower ends the cover-section 16 is detachably fastened to the outer face of the body portion 15 by means of snap-fasteners, the heads 18 of which are secured to the section 16 and the post or stem members 19 of which are secured to the body portion 15, and along its free edge the cover-section 16 is

5 detachably secured to the body portion 15 by one of the lower end snap-fasteners (18, 19) and by a series of properly distributed snap-fasteners whose heads 20 are secured to the section 16 and whose post or stem members 21 are secured to the body portion 15.

10 The back edge of the cover-section 16 is secured to the adjacent edge of the body portion 15 and to that of the side 11, in the manner more clearly illustrated in Fig. 5, in which it may be seen that the back edges of the section 16 and its lining 17, the adjacent edges of the body portion 15 and its lining 14 and the adjacent edges of the side 11 and its lining 13, are folded or flanged inwardly 15 at the corner edge of the bag and secured together by sewing 22. Between the facing in-turned edges of the cover section 16 and side 11 we interpose a folded strip 23 enclosing a cord 24 as a finish to the bag, the strip 23 being held by the sewing 22. The strip 23 and sewing 22 are continued entirely 20 around the side 11, said sewing below the lower ends of the cover-section 16 being through the inwardly folded adjacent edges 25 of the body-portion 15 and its lining and the side 11 and its lining and also through the folded strip 23, as shown at the lower left 30 hand side of Fig. 4, whereby the bag is given a corded back corner edge extending entirely around the bag.

35 The front side 12 is secured at its edges to the adjacent edges of the body portion 15 in a manner similar to that of securing the edges of the side 11 to the body portion 15, the edges of said side 12 with its lining and the adjacent edges of the body portion 15 with its lining being folded or flanged in- 40 wardly and the whole being secured together by a line of sewing 25 extending entirely around the bag. We interpose in the seam at the front peripheral edge of the bag a folded cored strip 26, which is secured by the sewing 25 and corresponds exactly with the strip 23 and cord 24 shown at the upper left hand side of Fig. 5, said cored strip 26 imparting to the front corner edge of the bag the same finish as that at the rear corner edge thereof. 45 The lines of sewing 22, 25 are concealed and thus do not mar the appearance of the bag.

50 The fabric of the cover-section 16 at the free edge and lower ends of said section, is folded under and seamed down, as indicated at 27, thereby securing the adjacent edge of the lining 17 and imparting a durable finish to the free edge portions of said section 16. The cover-section 16 extends frontwardly 55 over the top of the body portion 15 to about the front edge thereof, as shown in Figs. 2 and 4, and down the sides of said body-portion to about the horizontal middle portion thereof, said cover-section thus defining substantially a semicircle, while the body portion 15

defines a circle, and both making up the peripheral band portion 10 of the bag.

59 In the back seam at the top of the bag, joining the parts 11, 15, 16 together, we interpose one end of a flat handle strip 28 and secure the same by the sewing 22, and in the corresponding front seam at the top of the bag joining the parts 15, 12 together, we interpose a tab 29 and secure the same by the sewing 25, and on the free ends of said strip and tab we provide means for detachably securing them together so as to create a handle by which the bag may be carried or suspended, said securing means being of any suitable nature but preferably a snap-fastener whose head 30 is secured to the strip 28 and whose socket 31 is secured to the tab 29.

60 The body-portion 15 of the peripheral band 10 is, in its upper half, slit downwardly between its front and back edges and the material at said edges is folded outwardly, with the adjacent portions of the lining 14, and seamed down, as by a line of sewing 32, thereby dividing the upper half of the body portion 15 into two substantially equal sections 33, 34, which, when free to do so, may be turned outwardly from one another, the sides 11, 12 being flexible, and thereby provide an opening through which a hat may be placed within the bag or removed therefrom. Either section 33, 34 may be turned outwardly to open the bag or said sections may both be turned outwardly in a direction from each other to open the bag, as may be found to be convenient or necessary.

65 The bag may be held in closed condition by securing the cover-section 16 to the body section 34 by means of the snap-fasteners 18, 19, and 20, 21 and also by fastening the handle strip 28 to the tab 29, the bag then presenting the appearance illustrated in Fig. 2.

70 When it is desired to fully open the bag, the handle strip 28 will be free from the tab 29, and the cover-section 16 will, along its lower ends and front edge, be freed at the snap fasteners 18, 19 and 20, 21, and thereupon the cover-section 16 and body-section 33 may together be folded backwardly and the body-section 34 frontwardly, to fully open the top of the bag, or the bag may be opened by 75 turning the cover-section 16 and body-section 33 backwardly without disturbing the body-section 34, or by turning the body-section 34 frontwardly, as shown in Fig. 1, without disturbing the cover-section 16 and body-section 33.

80 The construction as thus far described presents a complete, novel, convenient, commodious, durable and attractive hat-bag, but as hereinbefore mentioned we preferably apply thereto means for reinforcing or stiffening the peripheral band 10 across its width, so that when the bags are placed flatwise one upon another while on display in a store or held in stock, the bags may not collapse under the 85

weight thus imposed upon them. A tier of the bags in a collapsed or flattened-out condition on a store counter would not present the most desirable appearance, even though on the other hand a purchaser might prefer a wholly soft or flexible bag. We therefore preferably apply along the inner surface of the peripheral band 10, a strip or strips of pasteboard or the like of about the same width as said band and of sufficient stiffness to prevent the collapse of the bags when placed flatwise on a counter or shelf. The bags may also be prevented from collapsing by stuffing them with paper, excelsior or other loose packing material, but that method is objectionable for several reasons, one being that the litter created by the packing material would not be permitted.

The band-reinforcement shown in the drawings consists of two substantially semi-circular strips 40, 41 of pasteboard, fibreboard or the like and of about the width of the band, the strip 40 being extended through the cover-section 16 at the back of the lining 17 thereof, as shown on an enlarged scale in Fig. 6, and the strip 41 being extended through the body-portion 15 below the cover-section 16 and at the back of the lining 14 thereof, as shown in Figs. 3, 4 and 6. The strips 40, 41 together define substantially a circle and by being in segmental form may be concealed behind the lining of the band 10, thereby leaving the lining to be exposed to a prospective customer when the bag is opened. We form a slit 42 (Fig. 6) in the lining 17 of the cover-section 16, at one end of said section, through which the stiffening strip 40 may be applied to and removed from said cover-section, and at the opposite side of the bag from said slit 42, we form a similar slit 43 (Fig. 3) in the lining 14 of the body-portion 15 through which the stiffening strip 41 may be applied to or removed from position behind the lining 14. The strips 40, 41 are entirely adequate for their intended purposes and with their use the linings of the bag are not concealed. In lieu of using the two strips 40, 41 a single strip having the combined length of the two strips may be made use of, such strip being placed in the bag against the lining of the peripheral band 10 and serving the reinforcing purposes of the two strips.

We have shown and described the preferred embodiment of the invention but do not wish to be limited to all of the details referred to, since these details admit of modification within the spirit and scope of our invention as defined in the appended claims.

What we claim as our invention and desire to secure by Letters Patent, is:

1. A hand-bag of the character described comprising a peripheral band, flexible disk sides seamed at their edges to the edges of said band, and a handle at the top of the bag,

said band comprising a body-portion and a segmental cover-section connected at one edge to one of said sides and thence extending across toward the other side, said body portion being open vertically below said cover-section to permit portions of said sides to be turned over outwardly on opening the bag, and said cover-section and body-portion having means for detachably securing the free edge of the cover-section to said body-portion on closing the bag.

2. A hand-bag of the character described comprising a peripheral band, flexible disk sides seamed at their edges to the edges of said band, and a handle at the top of the bag, said band comprising a body-portion and a segmental cover-section connected at one edge to one of said sides and thence extending across toward the other side, said body-portion being open vertically below said cover-section to permit portions of said sides to be turned over outwardly on opening the bag, said cover-section and body-portion having means for detachably securing the free edge of the cover-section to said body-portion, and said handle comprising a strip secured at one end in the seam at one side of the bag, a tab secured in the seam at the other side of the bag and means on the free ends of said strip and tab for detachably securing them together.

3. A hand-bag of the character described comprising a peripheral band, flexible disk sides seamed at their edges to the edges of said band, and a handle at the top of the bag, said band comprising a body-portion and a segmental cover-section connected at one edge to one of said sides and thence extending across toward the other side, said body-portion defining a circle and being open downwardly between its edges and below said cover-section, thereby forming at said portion two sections extending over the top of the bag below said cover-section and at their lower ends being integral with said body-portion, one of said body-sections being connected with said cover-section and said body-sections with the adjacent portions of said sides being adapted to be folded outwardly on opening the bag, and said cover-section and body-portion having means for detachably securing the free edge of the cover-section to said body-portion on closing the bag.

4. A hand-bag of the character described comprising a peripheral band, flexible sides seamed at their edges thereto and a handle at the top of the bag, said band comprising a body-portion and a segmental cover section permanently secured at one edge and adapted to transversely cover over the top of the bag, said body-portion being open vertically below said cover-section to permit portions of said sides to be folded over outwardly on opening the bag, and said cover-section and body-portion having means for detachably

securing the free edge of the cover-section to said body-portion on closing the bag.

5. A hand-bag of the character described comprising a peripheral band, flexible sides 5 seamed at their edges thereto and a handle at the top of the bag, said band comprising a body-portion and a segmental cover-section permanently secured at one edge and adapted to transversely cover over the top of the bag, 10 said body-portion defining a circle and being open downwardly between its edges and below said cover-section, thereby forming at said portion two body sections extending over the top of the bag below said cover-section 15 and at their lower ends being integral with said body portion, and said body sections with the adjacent portions of said sides being adapted to be turned outwardly on opening the bag, and said cover section and body portion 20 having means for detachably securing the free edge of the cover-section to said body-portion on closing the bag.

6. A hand-bag of the character described comprising a peripheral band having a fabric 25 lining, flexible sides having linings and having their edges and the edges of their linings seamed to the edges of said band and its lining, a handle at the top of the bag, and means 30 extending along the inner periphery of said band for transversely stiffening the same, said band comprising a body portion and a segmental cover-section secured at one edge and adapted to transversely cover over the top of the bag, said body-portion being open vertically 35 below said cover-section to permit portions of said sides to be folded over outwardly on opening the bag, and said cover-section and body-portion having means for detachably securing the free edge of the cover-section to 40 said body-portion on closing the bag.

7. A hand-bag of the character described comprising a peripheral band having a fabric lining, flexible sides having linings and having their edges and the edges of their linings 45 seamed to the edges of said band and its lining, a handle at the top of the bag, and a removable lining of pasteboard or the like of about the width of said band and extending closely along the inner periphery thereof for transversely stiffening the same, said band comprising a body portion and a segmental cover-section secured at one edge and adapted to transversely cover over the top of the bag, said body-portion being open vertically 50 below said cover-section to permit portions of said sides to be folded over outwardly on opening the bag, and said cover-section and body-portion having means for detachably securing the free edge of the cover-section to 55 said body-portion on closing the bag.

8. A hand-bag of the character described comprising a peripheral band having a fabric lining, flexible sides having linings and having their edges and the edges of their linings 60 seamed to the edges of said band and its lin-

ing, a handle at the top of the bag, and pasteboard or the like of about the width of said band and extending along the inner periphery of the band and concealed behind the fabric lining thereof for transversely stiffening said band, said band comprising a body portion and a segmental cover-section secured at one edge and adapted to transversely cover over the top of the bag, said body-portion being open vertically below said cover-section to permit portions of said sides to be folded over outwardly on opening the bag, and said cover-section and body-portion having means for detachably securing the free edge of the cover-section to said body-portion on closing the bag.

9. A hat bag of the character described formed of substantially self-collapsing material and shaped as a drum comprising a peripheral band, flexible disk sides seamed at their edges to the edges of said band, an opening in said band, a flap for said opening, a portion of the material of one of said sides also serving as a closure-flap, means for securing said flaps in closed position, and a strip handle secured at its ends to opposite edges of the bag.

Signed at New York city, in the county of New York and State of New York, this 16th day of August A. D. 1922.
